UNITED STATES PATENT OFFICE.

FRED C. WERBER, OF KINGSTON, PENNSYLVANIA.

TEXTILE SPINNER AND TWISTER.

Application filed November 1, 1924. Serial No. 747,320.

To all whom it may concern:

Be it known that I, FRED C. WERBER, a citizen of the United States, residing at Kingston, in the county of Luzerne and State of Pennsylvania, have invented certain new and useful Improvements in a Textile Spinner and Twister, of which the following is a specification.

This invention relates to textile machinery, and has particular reference to a means whereby a single thread may be spun or whereby a multiplicity of threads may be simultaneously doubled and twisted.

The primary object of the invention resides in the provision of apparatus, whereby a single revolution of the flier will occasion a double number of spins or twists in the thread.

This feature has heretofore been attempted, but the results have been invariably unsuccessful. This is mainly due to the fact that the thread bobbin or spool is disposed in end to end relation with the spindle and in slightly offset relation thereto.

During the operation of spinners or twisters of this nature, the bobbin will absolutely rotate with the spindle after the same has reached great speed and the results intended will not be accomplished. Attempts have been made to prevent the rotation of the bobbins with the spindles by the disposition of magnets adjacent the bobbins. This is an expensive proposition and the results intended have not been resultant.

It is therefore, an additional object of the present invention, to so dispose the bobbin with respect to the spindle that all liability of the bobbin rotating with the spindle will be overcome. This object is accomplished by the disposition of the spindle in a substantially horizontal manner, and then suspending the bobbin directly from the spindle, in such a manner that the weight of the bobbin will negative any liability of the same rotating about the spindle, during operation of the apparatus.

This object is further accomplished by constructing a bobbin supporting saddle, in such a manner that the spindle engaging surface of the saddle spindle engaging element contacts the spindle tangentially in more

than one plane, thereby minimizing friction by reduction in the area of contact, that would otherwise exist between the spindle and saddle during the operation of the spindle.

A further and important object is to provide a simple, but efficient form of saddle, whereby the bobbin may be readily attached to or removed from the spindle during the rotation thereof and whereby a minimum amount of friction will prevail between the spindle and saddle during rotation of the device.

In addition to the foregoing objects, a further beneficial result is provided, by supporting the bobbin beneath a substantially horizontal spindle. In the form of apparatus to which my invention relates, a great amount of space is required by the end to end relation of the bobbin and spindle. In my device, but small compass is required, in the supporting of the bobbin from the spindle.

With the foregoing and other objects in view, as the nature of the invention will be better understood, the same comprises the novel simple and practical form, combination, and arrangement of parts hereinafter more fully described, shown in the accompanying drawings and claimed.

In the drawings:

Figure 1 is a side elevation of the preferred embodiment of my invention.

Figure 2 is a front end elevation thereof.

Figure 3 is a detail fragmentary section, taken substantially upon the line 3-3 of Figure 2.

Figure 4 is a front end elevation, showing a pair of bobbins supported upon the spindle, for use in the doubling and twisting of a pair of threads.

Figure 5 is a detail perspective of a double-saddle that constitutes an essential part of the present invention.

Figure 6 is a side elevation of the device, the bobbin being supported in substantially horizontal relation with respect to the spindle, and

Figure 7 is a perspective of the saddle employed in supporting the bobbin in substantially horizontal relation.

In the drawings, I have disclosed but a single spindle and its associated bobbin or bobbins. However, it is to be understood that a battery of spindles are to be employed, for providing, together with suitable power means, a complete spinning and twisting machine.

First having reference to Figures 1, 2, and 3, the reference character 5 designates a 10 spindle of conventional form, that is suitably journaled at its inner end within the arms of a journal bracket 6, which is secured to one of the usual frame bars of a spinning or twisting machine. This spindle 15 is supported in a substantially horizontal manner, and is equipped with the usual belt pulley 7.

At the forward end of the spindle there is formed a pair of spaced annular grooves 20 8-8 for a purpose hereinafter to be more fully described. Associated with the forward end of the spindle is a bobbin supporting saddle designated generally 9. This saddle may be constructed from a 25 single strand of wire preferably of circular shape in cross section, that is so bent upon itself as to provide an arm portion 10, an upwardly bent right angular portion 11, and a pair of outwardly converging fingers 30 12-12, the ends of which are hooked, as at 13-13 for engagement in the channel portions of said spindle and this only upon a relatively small portion of the circumferential area thereof, as more clearly shown in 35 Figures 1 and 2. The bobbin A is disposed upon the arm 10 either before or after the saddle is positioned upon the spindle 5. The provision of the pair of hooks in engagement with the spindle, at spaced points, 40 negates any liability of horizontal swinging movement, of the bobbin, during rotation of the spindle. The weight of the saddle and bobbin absolutely prevents the rotation of the bobbin around or with the 45 spindle due to the saddle contacting the spindle at but a small portion of its circumferential area. By a careful review of Figure 3, it will be noted that the spindle engaging hooks of the bobbin saddle contact 50 with the spindle tangentially in planes parallel with and at right angles to the longitudinal plane of the spindle. This contact is, in reality a knife edge contact between the saddle hook and the spindle or 55 a ball point contact between the elements for obviously minimizing friction between the hooks and spindle during the rotation of the same which results in the proper suspension of the bobbins during rotation of the spindle 60 and their consequent non-rotation during high speed of the spindle, which is a feature in devices of this character not heretofore obtained.

Rigidly associated with the spindle at a 65 point adjacent the bearing 6 is a double

flier 14, preferably consisting of a single length of fine wire that may be passed through and secured within an opening of the spindle. This flier includes an elongated arm 15, upon each side of the spindle 70 5, and a short horizontal portion 16, at the end of each arm, the same being so bent as to provide a pair of spaced thread receiving eyes 17-17.

The spindle is formed with a longitudinal bore 18, and a pair of outlet passages 19. In use, after the bobbin has been supported upon the spindle, the thread is passed into the bore and then drawn out through either passage, after which it is drawn upwardly alongside of the proper arm of the flier, and passed through the eyes 17-17. The thread is then led forwardly to the usual drawing and spooling mechanism. During the rotation of the spindle 5, the thread will be spun between the flier and the bobbin and also between the flier and the drawing and spooling mechanism for thereby accomplishing two spins of the thread at each revolution of the flier.

The provision of the double armed flier overcomes any vibration of the spindle, and thereby lessens the liability of wobbling movement in the bobbin and its consequent jumping from the spindle or rotating therewith. However a single flier may be employed if desired.

In Figure 4, I have shown a pair of bobbins designated respectively B and B', supported perpendicularly with respect to the spindle 5'. In this instance either one or two bobbins may be associated with the spindle, for spinning a single thread, or for spinning and twisting a pair of threads. In this instance, a saddle 9' is provided, which may also be constructed from a single piece of wire, so bent as to provide a pair of vertical arms 20-20, interconnected at their lower ends by a cross bar 21, which is provided with a pair of vertical and outwardly converging fingers that are hooked, at their upper ends, as at 22, whereby this saddle may be also conveniently disposed, upon the spindle, as clearly shown in Figure 4. In this instance also, the threads from the bobbins are properly injected into the bore of the spindle, and then drawn outwardly through either opening and passed to the proper flier.

In Figure 6, the bobbin A'' is supported in substantially horizontal relation to the spindle 5''. The bobbin in this instance is, however, at a slight inclination with respect to the spindle, for preventing the disengagement of the same from the saddle 9'' provided in this instance. This saddle is clearly shown in Figure 7, and may also be formed of a single length of wire, so bent as to provide a bobbin receiving arm 23, and a spaced parallel arm portion 24, that is pro-

vided, at its end, with vertical fingers 25, that are hooked, as at 26, for engagement over the grooves of the spindle 5".

By referring to the drawings it will be noted that the hook members of the saddles are so constructed as to have their ends engaged beneath the spindles when disposed thereon. This feature is provided in order that the ends of the hooks will strike the spindles and prevent accidental displacement of the bobbins, should the saddles, for any reason, tend to rise vertically upon the spindles.

From the foregoing description, when considered in conjunction with the accompanying drawing, it will be at once apparent, to those skilled in the textile art, that I have provided a highly novel and efficient form of spinner and twister, and one wherein the bobbin or bobbins will be absolutely prevented from rotating with or around the spindle, during the operation of the device, and wherein a double amount of spins or twists will be occasioned, during the rotation of the flier.

In addition to this, the relation of the bobbin or bobbins with respect to the spindle will greatly reduce the size of the complete machine, which is a decided advantage.

Even though I have shown and described, the preferred embodiments of the present invention, I do not wish to be limited to the disclosure, in so far as in the future practice of the invention, certain changes or modifications may be made, without departing from the spirit and scope of the appended claims.

Having thus described my invention, what I claim as new and desire to secure by Letters Patent, is:

1. In a device of the character described, a substantially horizontally disposed spindle, a bobbin, a bobbin supporting saddle for maintaining the bobbin in suspended relation with respect to the spindle having a member hooked at one end for quick detachable engagement with the upper surface of the spindle, and a flier operable by the spindle.

2. In a device of the character described, a substantially horizontal spindle, a bobbin, a saddle for suspending the bobbin from the spindle which has a pair of members for quick detachable engagement with the spindle at spaced points thereon, whereby the bobbin may be suspended from the spindle and a flier operable by the spindle.

3. In a device of the character described, a horizontal spindle, a bobbin, a bobbin supporting saddle for maintaining the bobbin in suspended relation with respect to the spindle having means for engagement upon only the top side of the spindle, said spindle being formed with means for preventing the longitudinal movement of the saddle thereon, and a flier operable by the spindle.

4. In a device of the character described, a hollow spindle having points of thread ingress and egress, a bobbin, a spindle engaging saddle having means whereby the bobbin is retained in suspended relation with respect to the spindle, and a flier secured to the spindle rearwardly of the point of thread egress.

5. In a device of the character described, a single length spindle, a bobbin, quick detachable means for supporting the bobbin in suspended relation with respect to the spindle and substantially at right angles thereto, and a flier operable by the spindle.

6. In a device of the character described, a single length hollow spindle, a bobbin, means for supporting the bobbin upon the spindle substantially at right angles thereto whereby the thread may be fed directly to the spindle at its forward end without intermediate guide means and a flier operable by the spindle.

7. In a device of the character described, a horizontal spindle, a pair of bobbins, means for supporting the bobbins in suspended relation with respect to the spindle in a substantially vertical manner, and a flier operable by the spindle.

8. In a device of the character described, a spindle, a pair of bobbins between which the spindle is adapted to extend, means for supporting the bobbins in suspended relation with respect to the spindle in a substantially vertical manner, and a flier operable by the spindle.

9. In a device of the character described, a single length hollow spindle, a bobbin, means for supporting the bobbin in suspended relation with respect to the spindle in such a manner that the inlet end of the spindle will be intermediate the heads of the bobbins whereby the thread may be fed into the spindle without intermediate guide means, and a flier operable by the spindle.

10. In a device of the character described, a spindle, a bobbin, a saddle for supporting the bobbin in suspended relation with respect to the spindle, and means for preventing the accidental displacement of the saddle from the spindle and a flier operable by the spindle.

11. In a device of the class described, a spindle, a bobbin, a saddle for detachably receiving the bobbin, cooperating construction between the saddle and the spindle whereby the saddle may be associated in suspended relation with respect to the spindle and removed therefrom in a rapid manner, said construction of the spindle and saddle forming permanent parts of the respective elements, and a flier operable by the spindle.

12. A device of the character described including a flier fixed on a single length rotating spindle so constructed that the end

of the flier passes both ends of a suspended delivery bobbin at each revolution of the spindle.

13. In a device of the class described, a spindle, a bobbin, a saddle for supporting the bobbin in suspended relation with respect to the spindle and having spindle attachment means for contact with the spindle in tangential relation in more than one plane.

In testimony whereof I affix my signature.

FRED C. WERBER.
